UNITED STATES PATENT OFFICE.

JOHANNES GRIMME, OF GODESBERG-ON-THE-RHINE, GERMANY, ASSIGNOR TO THE FIRM OF HERMANN HEINRICH BÖKER & CO., OF BONN, GERMANY.

WIRE STRETCHER.

Application filed April 5, 1922. Serial No. 549,872.

To all whom it may concern:

Be it known that I, JOHANNES GRIMME, a citizen of the German Republic, residing at Godesberg-on-the-Rhine, Prussia, Germany, have invented certain new and useful Improvements in Wire Stretchers (for which I have filed applications in Germany July 5, 1920, and October 4, 1921), and of which the following is a specification.

- 10 This invention relates to a wire stretcher which consists of a plate-shaped body having nicks in the ends and in the upper edge a slit which terminates in a circular enlargement. The stretching is effected, according to 15 this invention, in such a manner that the wire is inserted in the circular enlargement at the inner end of the slit of the wire stretcher, whereupon the stretcher is turned around its transverse axis so that the wire 20 is inserted in the lateral nicks, whereby the slipping off of the stretcher in a lateral direction is prevented.

In order to prevent the stretcher from turning in the opposite direction and the 25 wire be unwound under the pull of the stretched wire a fork-shaped extension is arranged at one end of the stretcher and this extension is bent so that its fork-shaped end embraces the wire when the stretcher turns 30 back, the stretcher being thus held by the wire. Instead of one fork-shaped extension two such extensions can be provided which are bent in opposite directions.

With the same object in view, viz., to prevent the unwinding of the wire from the 35 stretcher, the plate-shaped body can have also deep lateral nicks the arms of which can be bent together after the winding up of the wire. The nicks can however be also 40 leaf-shaped in order to hold the stretcher upon the stretched wire. The stretched wire engages in this case with the arc-shaped parts of the nicks. In order to prevent this wire being cut by the stretcher the parts 45 around which the wire is wound are rounded off.

For facilitating the gripping of the stretcher with tongues specially designed for this purpose a notch is provided which 50 is parallel with the long side of the body.

In order that the invention may be clearly understood, I shall proceed to describe the

same with reference to the form of construction shown by way of example on the accompanying drawing, wherein:

55

Fig. 1 shows in elevation a wire stretcher with one fork-shaped extension at one end.

Fig. 2 is a plan view of Fig. 1.

Fig. 3 shows the stretcher turned 90° from the position shown in Figure 2 after 60 having stretched the wire.

Fig. 4 shows the stretcher turned 180° from the position shown in Figure 3.

Fig. 5 shows in plan view a stretcher with 65 a fork-shaped extension at each end.

Fig. 6 shows a wire stretcher which has deep nicks in the ends and

Fig. 7 is a plan view of Figure 6.

Fig. 8 shows the wire stretcher of Fig. 6 with the arms bent together.

70

Fig. 9 shows a wire stretcher with leaf-shaped nicks.

A plate-shaped body 1 has nicks 2 at the two ends and a slit 3 in the upper edge, this slit terminating in a circular enlargement 75 the diameter of which is greater than the width of the slit. The edges of the nicks and of the circular enlargement 4 are rounded off in order to prevent the wire being cut or damaged by the stretcher. A notch 5, 80 arranged parallel to a long side of the body 1 serves to facilitate the gripping of the stretcher with tongues.

At one of the ends of the stretcher an extension 6 is arranged which terminates 85 in a fork 7.

The slightly stretched wire 8 is inserted through the slot 3 into the circular enlargement 4 whereupon the stretcher is turned as shown on Figs. 3 and 4 to stretch the wire. 90 To prevent the stretcher from turning back the fork-shaped end 7 of the extension 6 is placed upon the wire. If it should be necessary to further stretch the wire the stretcher can be turned several times in the manner 95 shown in Fig. 4. The fork-shaped end of the extension is again made to ride upon the wire so that the stretcher cannot move back automatically.

Two fork-shaped extensions can be provided as shown in Fig. 5, one at each end of the stretcher so that the stretcher is twice 100 ensured against back rotation.

According to the form of construction

shown in Fig. 6 the stretcher consists of a body 9 which has deep narrow nicks 10, one in each end.

The slit 11 inwardly extending from one of the long sides of the body 9 is semi-circular at its inner end. The arms 12 formed by the nicks 10 are arranged so that they can be bent together after the winding up of the wire in order to hold the wire securely 10 in the stretched position (Fig. 8).

According to the form of construction shown in Fig. 9 the body 13 has leaf-shaped nicks 14. After the wire has been wound up on the stretcher this stretcher is 15 placed so that the stretched wire engages with the arc-shaped parts 15 of the leaf-shaped nicks 14 whereby the turning back of the stretcher is prevented. To further 20 secure the stretcher in its position upon the stretched wire, the arms can be bent together.

Claims:

1. As a new article of manufacture a wire stretcher generally oblong in shape, provided in one of its longer sides with a notch, and provided in each of its shorter sides with a notch, and having an extension terminating in a laterally bent notched portion. 25
2. As a new article of manufacture a wire stretcher generally oblong in shape formed of a sheet of metal, provided in one of its longer sides with a notch, and provided in each of its shorter sides with a notch, and having an extension terminating in a laterally bent notched portion. 30
3. As a new article of manufacture a wire stretcher generally oblong in shape, provided in one of its longer sides with a notch, and provided in each of its shorter sides with a notch, and having an integral 35 extension terminating in a laterally bent notched portion.
4. As a new article of manufacture a

wire stretcher generally oblong in shape 45 formed of a sheet of metal, provided in one of its longer sides with a notch, and provided in each of its shorter sides with a notch, and having an integral extension terminating in a laterally bent notched portion. 50

5. As a new article of manufacture a wire stretcher generally oblong in shape, provided in one of its longer sides with a notch enlarged at its bottom, and provided in each of its shorter sides with a notch larger than the notch in the long side, and having an extension terminating in a laterally bent notched portion. 55

6. As a new article of manufacture a wire stretcher generally oblong in shape, 60 provided in one of its longer sides with a notch enlarged at its bottom, and provided in each of its shorter sides with a notch larger than the notch in the long side, and having an integral extension terminating 65 in a laterally bent notched portion.

7. As a new article of manufacture a wire stretcher provided with a pair of oppositely placed notches and a third notch 70 lying intermediate said pair of notches, said stretcher having an extension terminating in a laterally bent notched portion. 75

8. As a new article of manufacture a wire stretcher provided with a pair of oppositely placed notches and a third notch 75 lying intermediate said pair of notches, said stretcher having an extension terminating in a laterally extending wire engaging portion.

In testimony whereof I affix my signature 80 in presence of two witnesses.

JOHANNES GRIMME.
